UNITED STATES PATENT OFFICE.

CLIFTON L. BUNDY, OF PHILADELPHIA, PENNSYLVANIA.

DESIGN FOR AN INSULATOR.

46,243.

Specification for Design.

Patented Aug. 11, 1914.

Application filed June 3, 1914. Serial No. 842,787. Term of patent 14 years.

To all whom it may concern:

Be it known that I, CLIFTON L. BUNDY, a citizen of the United States, and a resident of Philadelphia, Pennsylvania, have invented a new, original, and ornamental Design for Insulators, of which the following is a specification, reference being had to the accompanying drawings, in which:

Figure 1, is a perspective view of my new and ornamental design for an insulator; Fig. 2, is a sectional view on the line 2—2, Fig. 1, and Fig. 3, is a sectional view on the line 3—3.

The insulator forming the subject of my ornamental design is substantially symmetrical; having the same contour when reversed and viewed from diametrically opposite points.

I claim:

The ornamental design for an insulator as shown and described.

CLIFTON L. BUNDY.
